UNITED STATES PATENT OFFICE.

WILLIAM E. BLAIR, OF BAY CITY, MICHIGAN.

ENGINE.

960,797.

Specification of Letters Patent. Patented June 7, 1910.

Application filed January 21, 1908. Serial No. 412,005.

To all whom it may concern:

Be it known that I, WILLIAM E. BLAIR, a citizen of the United States, residing at Bay City, in the county of Bay and State of Michigan, have invented new and useful Improvements in Engines, of which the following is a specification.

This invention relates to internal combustion engines; and it has for its object to produce a gas or gasoline engine of the two cycle type which shall possess superior advantages in point of simplicity, durability and general efficiency, and particularly in the control of the inlet and exhaust ports.

With these and other ends in view which will readily appear as the nature of the invention is better understood, the same consists in the improved construction and novel arrangement and combination of parts which will be hereinafter fully described and particularly pointed out in the claim.

In the accompanying drawing has been illustrated a simple and preferred form of the invention embodied in a vertical engine; it being however understood that no limitation is necessarily made to the precise structural details therein exhibited, but that changes, alterations and modifications within the scope of the invention may be resorted to when desired, and that the essential features of the invention may be employed in a horizontal engine.

In the drawing, Figure 1 is a vertical sectional view taken through the cylinder and piston of an engine constructed in accordance with the invention. Fig. 2 is a sectional detail view taken through the cylinder on the plane indicated by the line 2—2 in Fig. 1 and looking in the direction of the arrows. Fig. 3 is a sectional detail view of the cylinder taken on the plane indicated by the line 3—3 in Fig. 1 and looking in the direction of the arrows. Fig. 4 is a sectional detail view taken horizontally through the cylinder on the plane indicated by the line 4—4 in Fig. 1.

Corresponding parts in the several figures are denoted by like characters of reference.

The cylinder C having the cooling chamber 10, and the hollow piston P have been shown of ordinary conventional construction. In Fig. 1 of the drawings the piston has been shown at the lower limit of its stroke.

The cylinder is provided at one side thereof with the admission port 5 and with an

exhaust port 6; at its opposite side the cylinder is provided with the by-pass 7 having the terminal ports or apertures 8 and 9 at its lower or inlet and upper or delivery ends 60 respectively.

The entrance port 5 is provided at its lower edge with a V-shaped triangular notch or recess 5' and a similar V-shaped triangular notch or recess 6' is formed at the upper 65 edge of the exhaust port; these notches will conduce to a gradual opening of the entrance and exhaust ports respectively upon the up stroke and the down stroke of the piston. In like manner the port or aperture 9 at the upper or delivery terminal of the by-pass 7 is provided at its upper edge with a V-shaped triangular notch, designated 9'; and it is to be observed that the total height of the port 9, including the 75 notch or recess 9', is equal to the total height of the port or aperture 8 at the lower terminal of the by-pass; the ports or apertures 8 and 9 are of equal width or transverse extent, but the port 9 is in general, and except 80 at the center where the notch 9' is formed, of less height or vertical extent than the port 8; and it follows that the area of the port or aperture 8 exceeds that of the port or aperture 9. By thus relatively proportioning the ports 8 and 9, the charge is permitted to freely enter the by-pass through the open port 8 and quickly flow to the port 9 for gradual admission into the cylinder the instant said port 9 is opened by the piston, the decreased area of the port 9 and the mode in which it is gradually opened by the piston, however, preventing such charge from rushing too rapidly into the cylinder.

The piston P is of the usual inverted cup 95 shape, and it is provided with a port or aperture 12 adapted to register with the ports 8, 9 at the ends of the by-pass 7 in order to permit the charge to pass from the lower end of the cylinder to the explosion 100 chamber at the upper end of the latter.

When the piston is at the upper limit of its movement, the entrance port 5 will be uncovered for the passage of the charge from the carburetor into the lower end of 105 the cylinder; as the piston descends and approaches the lower limit of its movement, the port 9 at the upper end of the by-pass 7 will be opened gradually to the passage of the charge into the explosion chamber, and 110 the objectional sudden rush of the charge will be averted. In like manner the exhaust

and admission ports will be opened slowly and gradually owing to the peculiar shape of said ports. Sudden and loud explosions will thus be avoided and the operation of 5 the machine is greatly improved.

It will be observed that the delivery end 9' of the by-pass is arranged opposite the exhaust outlet 6, but terminates in the plane below the top of the same. To more fully 10 state the purpose of the peculiar construction of this outlet port 6, it is well known that in the ordinary construction of engine, where the outlet port is suddenly opened full wide, the spent gases under high pressure 15 sure discharge suddenly with full force, resulting in the production of a loud and objectionable noise. By the provision of the tapering notch or recess 6' this objection is overcome, as the piston in uncovering said 20 recess before uncovering the body of the port allows of the escape of the spent gases to an extent to reduce the pressure to a material degree, so that upon the opening of the port, the gases will easily discharge 25 without the objectionable noise referred to.

The purpose of providing the fuel inlet port 5 with the tapering notch or recess 5', which is first uncovered by the piston on its compression stroke, is to adapt the port to 30 open slowly and permit of a more thorough admixture of the gasoline and air before the charge enters the cylinder. In the ordinary engine where the inlet port is quickly opened, a too rapid entrance of the fuel 35 charge is liable to occur, thus diminishing the efficiency on account of the imperfect admixture of the gasoline and air, and experience has demonstrated that the slower the admission of the charge can be effected in an engine of the three port type 40 the greater the efficiency of action. It will be understood that by first gradually uncovering the notch 5', and then uncovering the port until it is fully open, the entrance of the charge is retarded just sufficiently to secure an effective combination 45 of the gasoline with the air, thus producing a much more satisfactory mixture.

The inlet end 8 of the by-pass 7 is arranged 50 opposite the inlet port 5, and by reason of the fact that such end 8 is of greater area than the delivery end 9 of the by-pass, it will be understood that provision is made for the rapid passage of the charge from 55 said inlet end to said delivery end when the port 12 in the piston registers with the inlet end. By this means the charge is fed up ready to enter the cylinder through the port 9 as soon as the latter opens, thus preventing 60 any impediment to the rapid flow of

the charge to the upper portion of the cylinder after the admixture has been obtained. When the piston moves downwardly on its working stroke, it first uncovers the notch 6' and a portion of the body of the port 6 to 65 reduce the high pressure of the spent gases as above described and then uncovers the notch 9', thus allowing a portion of the fresh fuel mixture to enter the upper portion of the cylinder before the spent gases have 70 fully discharged. As a result of this operation, the admitted fresh vapor will assist in displacing the remainder of the spent gases above the piston before the latter on its return stroke closes said port, by which the 75 exhaust of the spent gases will not only be facilitated, but the retention of any portion thereof and their admixture with the fresh fuel prevented, whereby a positive explosion of the fresh charge will be insured as 80 long as the igniting means is in good working order.

It will thus be seen that the ports as constructed and arranged work in harmony to 85 reduce the noise and increase the efficiency of operation of the engine.

Having thus described the invention, what is claimed is;—

In an internal combustion engine, a cylinder provided at one side with an exhaust 90 port and a fuel inlet port, arranged one above the other, said exhaust port being provided in its upper edge and said fuel inlet port in its lower edge with a V-shaped notch or recess, said cylinder also being provided 95 in its opposite side with a by-pass having inlet and delivery ends of equal widths arranged respectively opposite said fuel inlet and exhaust ports, the said delivery end being provided with a V-shaped notch or recess at its upper edge terminating below the corresponding notch or recess of the exhaust port and the total height of said delivery end, including said notch or recess, being equal to the height of the inlet end, whereby 100 the latter is of greater area than the delivery end, and a hollow piston provided with a port to communicate with the inlet end of the by-pass, the exhaust port and ends of the by-pass being arranged to be uncovered 1 near the end of the down stroke of the piston and the inlet port arranged to be uncovered near the end of the up-stroke of the piston.

In testimony whereof I affix my signature 1 in presence of two witnesses.

WILLIAM E. BLAIR.
